MERCURY SWITCH

Carl H. Larson, Elkhart, Ind., assignor to The
Adlake Company, a corporation of Illinois

Application December 24, 1934, Serial No. 758,879

17 Claims. (Cl. 200—97)

This invention relates to a mercury switch adapted to alternately open and close an electrical circuit as long as the switch is operated above a predetermined minimum frequency, but which if that frequency is not reached, or if the intermittent operation of the switch ceases, will automatically close the circuit through the switch.

These and further objects and advantages will become apparent as the disclosure proceeds and the description is read in conjunction with the accompanying drawings, in which

Figs. 1-4 inclusive show various positions of a back contact switch made in accordance with this invention;

Figs. 5-7 inclusive show various positions of a front contact switch made in accordance with this invention.

But this specific illustration and the corresponding specific description are for the purpose of disclosure only and are not to be construed as imposing limitations on the claims except as required by the prior art.

The switches of this invention are of the type in which a magnetically controlled plunger or displacer determines by its position within the switch the height of a mercury column and hence the condition of the electrical circuit through the switch. A coil 10 is associated with each switch and is intermittently energized, as for example by a synchronous motor 11 driving a cam 12 which operates a circuit breaker 13 in a circuit which includes a coil 10 and an electromotive force 14. Other means for intermittently energizing the coil 10 may, of course, be used.

The switches are mounted within the coil 10 and the air gap for operating the switches is fixed by providing pole sleeves 15 and 16 of magnetic material connected exteriorly by an iron yoke 17.

The switches are held in place by sleeves 18 of non-magnetic material which yieldingly grip the switch envelopes in the region of the air gap.

Back contact switch (Figs. 1-4)

The back contact switch, generally designated 19, shown in Figs. 1-4 comprises a switch envelope 20, preferably of glass, through the bottom of which electrodes 21 and 22 are sealed. The central electrode 21 is surrounded by a glass sleeve 23 for the major portion of its length, and the bared end of the electrode is bent over with its end 24 extending below the top of the insulating sleeve.

The envelope contains a quantity of mercury 25, the level of which with respect to the central

electrode 22 is determined by the position within the envelope of a displacer or plunger 26.

As common with switches of this general character, the envelope is evacuated and filled with an inert gas (such as helium hydride, helium, 5 hydrogen, or the like) before being sealed off at 27.

The displacer 26 comprises an iron sleeve 28, interiorly fitted with an elongated glass thimble 29, both ends of which project beyond the iron 10 sleeve 28. Guide washers 30 provided at intervals along their peripheries with lugs engaging the walls of the envelope fit over the projecting ends of the glass thimble 29 and guide the displacer in its vertical movement within the envelope. The washers are held in place by springs 31 which also serve to protect the switch during 15 switching.

The top of the displacer is equipped with a time delay element, generally designated 32, 20 which permits gas to pass slowly to and from the interior of the displacer whenever there is a gas pressure differential which tends to move the gas.

The time delay element in the present embodiment of the invention consists of a small opening 25 33 in the top wall of the glass thimble, 29, and plugs 34 and 35 of cotton separated by a layer of ceramic powder 36. The resistance which the cotton plugs and ceramic powder offer to the passage of gas may be adjusted by the tightness 30 with which the wads are packed in the thimble, and the amount of powder that is used.

The displacer has an opening 37 through its side wall at a point just above the level of the mercury when the switch is in de-energized position (see Fig. 1). In this position, the mercury 35 level is such that the electrodes 21 and 22 are bridged by the mercury.

As soon as the enlarged portion of the cam which is rotated in the direction of the arrow 40 strikes the circuit breaker 13, the coil 10 becomes energized and the magnetic flux between the poles 15 and 16 draws the plunger 26 down to the position shown in Fig. 2.

This downward movement of the plunger 45 causes the mercury level on the outside of the displacer to rise, but the gas entrapped within the space 38 forces the mercury within the displacer away from the bared end of the electrode 21, thus opening the circuit. The difference in 50 the outside and inside mercury levels creates a gas pressure differential which tends to become equalized as the gas within the space 38 slowly passes through the time delay element 32, and as this equalization process takes place, the mercury 55

level on the outside of the displacer gradually falls and that on the inside gradually rises. However, before the mercury on the inside of the displacer has time to make contact with the 5 end 24 of the electrode 21, the cam 12 has rotated a sufficient amount to bring the circuit breaker 13 to the rearward edge of the enlarged portion of the cam (see Fig. 3) and as soon as the circuit through the coil 10 is opened, the displacer 26 rises by its buoyancy to the position shown in Fig. 1 momentarily carrying with it a quantity of mercury within the displacer. At the instant, however, when the opening 31 rises above the outside mercury level (which of course 10 falls rapidly as the displacer rises), the mercury column within the displacer is undermined and the switch parts almost instantaneously take the position shown in Fig. 1 with the mercury level the same on the inside and outside of the displacer. 15

Inasmuch as the circuit through the electrodes 21 and 22 is closed when the coil is de-energized, it naturally follows that any lower position of the displacer will effect the closing of the circuit 25 if the time delay element 32 is given an opportunity to equalize the gas pressures on the inside and outside of the displacer. For example, should the coil 10 become permanently energized as distinguished from intermittently energized 30 by reason of an open circuit through the motor 11, the mercury in the switch would finally level off as shown in Fig. 4, leaving the circuit through the switch closed.

This feature is very important in many circuits where it is desirable to have the circuit 35 through the switch closed in case the intermittent energization of the switch ceases.

Front contact relay (Figs. 5-7)

40 The front contact switch, generally designated 45, shown in Figs. 5-7 inclusive, performs the same function as the switch shown in Figs. 1-4 with respect to closing the circuit through the switch whenever the intermittent energization of 45 the coil ceases.

The switch comprises an envelope 46, electrodes 47 and 48, a mercury fill 49, an insulating sleeve 50 around the central electrode 47, and a displacer generally designated 51. In so far as 50 these parts resemble the back contact switch shown in Figs. 1-4 inclusive, they will not be described in detail here, and corresponding reference characters will be used.

When the coil 10 is energized, the displacer is 55 lifted completely out of the mercury, and the mercury level within the switch envelope is such that it contacts with the bared end of the electrode 47 thus closing the circuit between the electrodes 47 and 48. When the cam 12 rotating 60 in the direction of the arrow opens the circuit through the coil 10, the displacer 51 falls by gravity to the position shown in Fig. 6 forcing mercury away from the central electrode 47 due to the gas pressure differential between the inside and outside of the displacer.

In normal operation, the coil 10 is again energized before the mercury column within the displacer has a chance to make contact with the bared end of the central electrode 47 by the 70 escapement of gas through the time delay element 32, thus lifting the displacer to the position shown in Fig. 5. As the plunger moves upwardly due to energization of the coil, a column of mercury is carried up within the displacer, but as 75 soon as the outside mercury level falls below

the bottom of the glass thimble 29, the mercury falls away from the displacer so that the switch parts take the position shown in Fig. 5 almost instantly upon energization of the coil 10.

Should, for any reason, the intermittent energization of the coil 10 cease, as for example by an open circuit through the motor 11, the mercury column within the displacer will have sufficient time to rise and close the circuit through the electrodes 47 and 48 (see Fig. 7). 10

As in the back contact switch, any position of the displacer effects the closing of the circuit between the electrodes 47 and 48 if the time delay 15 32 is given a sufficient time to operate. If not, the switch operates as a front contact switch.

When the principles underlying the invention are fully understood, many modifications will suggest themselves to those skilled in the art. For example, tilting type mercury switches may be equipped with time delay elements to accomplish the desired functions. 20

The circuit breakers disclosed herein are not limited in their use to an intermittently operated control circuit. There may be situations in which it is desirable to open a circuit for a given period 25 of time and then close it again, this entire function to take place upon the happening of some event, as for example, the energization or de-energization of a relay coil. The switches of this invention are admirably suited to this purpose. 30

I claim:

1. In a circuit breaker of the class described, comprising a switch envelope, a mercury fill, spaced electrodes in the envelope, means for shifting the mercury to change the condition of the circuit through the electrodes, a time delay element adapted to restrain the movement of mercury toward but not away from one of said electrodes, the quantity of mercury in the envelope and the elevation of the electrodes being such 40 that the electrodes are bridged by mercury except when the time delay element is temporarily withholding the mercury from said one electrode.

2. In a circuit breaker of the class described comprising a switch envelope, a mercury fill, 45 spaced electrodes in the envelope, a displacer for shifting the mercury level to change the condition of the circuit through the electrodes, a time delay element adapted to restrain the movement of mercury toward one of said electrodes, the 50 quantity of mercury in the envelope and the elevation of the electrodes being such that the electrodes are bridged by mercury at all positions of the displacer with the exception of the period during which the time delay element is functioning to restrain the movement of mercury toward said one electrode.

3. A circuit breaker of the class described comprising a switch envelope, a mercury fill, spaced electrodes in the envelope, a displacer telescoped 60 over one of the electrodes for shifting the mercury to change the condition of the circuit through the electrodes, a time delay element carried by the displacer and comprising a restricted gas passage for restraining the movement of mercury toward, but not away from, said electrode, the quantity of mercury in the envelope and the elevation of the electrodes being such that the electrodes are bridged by mercury except when the time delay element is temporarily withholding 65 the mercury from said one electrode.

4. A circuit breaker of the class described comprising a switch envelope, a mercury fill, spaced electrodes in the envelope, means including a plunger for shifting the mercury to change the 75

- condition of the circuit through the electrodes, a time delay element telescoped over one of said electrodes and comprising a restricted gas passage for restraining the movement of mercury 5 toward said electrode, the quantity of mercury in the envelope and the elevation of the electrodes being such that the electrodes are bridged by mercury not only when the plunger is in its raised position, but also when in lowered position, except for the period during which the time delay element is functioning to restrain the movement of mercury toward said one electrode. 10
5. In a circuit breaker of the class described, a switch envelope, spaced electrodes sealed through the envelope, a mercury fill, means to shift the mercury to change the condition of the circuit through the electrodes, and a time delay element associated with one of the electrodes adapted to delay the movement of mercury toward, but not 20 away from, circuit closing position, the quantity of mercury and the elevation of the electrodes being such that the electrodes are bridged by mercury except when the time delay element is by its action restraining the movement of mercury toward one said electrode. 25
6. In a mercury switch, a switch envelope, spaced electrodes in the envelope, a mercury fill adapted to be manipulated to make or break an electrical circuit through the electrodes, a time 30 delay element for restraining the movement of mercury toward circuit closing position, the quantity of mercury and the elevation of the electrodes being such that the mercury bridges the electrodes whenever the mercury within the 35 envelope is at rest.
7. In a circuit breaker adapted to open and close an electrical circuit whenever the circuit breaker is intermittently operated at or above a predetermined frequency, the combination of 40 a container, a pair of electrodes in the container, a quantity of mercury in the container adapted to be moved with relation to the electrodes to open or close the electrical circuit through the electrodes, and means within the container for 45 limiting the time during which the circuit through the electrodes may under any circumstances continuously remain open, said means including a time delay element associated with one of the electrodes. 50
8. In a circuit breaker adapted to open and close an electrical circuit whenever the circuit breaker is intermittently operated at or above a predetermined frequency, the combination of 55 a container, a pair of electrodes in the container, a quantity of mercury in the container, and movable means for shifting the mercury with relation to the electrodes to close or open the electrical circuit through the electrodes, said means, mercury and electrodes being so proportioned as 60 to cooperate to close the circuit through the electrodes after said means remains at rest for a predetermined period of time at any point in its movement. 65
9. A mercury switch comprising a switch envelope, spaced electrodes having bared portions 65 therein, a mercury fill normally bridging the electrodes, a hollow plunger telescoped over one of the electrodes and movable between an upper position and a lower position for temporarily opening the circuit through the electrodes when the plunger is intermittently operated at or above a predetermined frequency, the parts being proportioned so as to cause the mercury to bridge the electrodes when the plunger is in its upper position and to be 70 displaced from one of the electrodes when the 75
- plunger is in its lower position, and means associated with the plunger, including a time delay device, for restoring the displaced mercury to bridging relation with the electrodes after the plunger remains in its lower position for a predetermined period of time. 5
10. In a relay, a coil, a mercury switch associated with the coil and comprising a switch envelope, a mercury fill, a pair of electrodes in the envelope, means responsive to the coil for shifting the mercury fill, said fill, electrodes and means cooperating to bridge the electrodes with mercury at all times except when the coil is being alternately energized and deenergized in excess of some predetermined frequency. 10
11. A mercury switch comprising an upright switch envelope, spaced electrodes having bared portions therein, a mercury fill normally bridging the electrodes, a hollow plunger telescoped over one of the electrodes and movable downwardly to displace the fill from said electrode and open the circuit, said plunger having an opening in its side wall for admitting gas to the plunger when the level of mercury outside the plunger is at or below the opening and having a time delay means operable on the gas in the plunger above said opening, said means comprising a restricted gas passage for relieving pressure in the plunger and permitting the mercury therein to rise to bridge the electrodes. 15
12. A back contact relay adapted to open and close an electrical circuit whenever the relay is intermittently operated at or above a predetermined frequency, said relay comprising the combination of a container, a pair of electrodes in the container, a quantity of mercury in the container, movable means for shifting the mercury with relation to the electrodes to close or open the electrical circuit through the electrodes, and a coil for operating said movable means to shift the mercury to open the circuit through the electrodes when the coil is energized and close the circuit when the coil is deenergized, said means, quantity of mercury and electrodes being so proportioned as to cooperate to close the circuit through the electrodes after said means remains at rest for a predetermined period of time at any point in its movement. 20
13. A back contact relay adapted to open and close an electrical circuit whenever the relay is intermittently operated at or above a predetermined frequency, said relay comprising the combination of a container, a pair of electrodes in the container, a quantity of mercury in the container, movable means for shifting the mercury with relation to the electrodes to close or open the electrical circuit through the electrodes, and a coil for operating said movable means to shift the mercury to open the circuit through the electrodes when the coil is energized and close the circuit when the coil is deenergized, said means, quantity of mercury and electrodes being so proportioned as to cooperate to close the circuit through the electrodes after said coil remains energized for a predetermined period of time. 25
14. A back contact relay adapted to open and close an electrical circuit whenever the relay is intermittently operated at or above a predetermined frequency, said relay comprising the combination of a container, a pair of electrodes in the container, a quantity of mercury in the container, movable means for shifting the mercury with relation to the electrodes to close or open the electrical circuit through the electrodes, a time delay device associated with the container, and a coil for operating said movable means to shift 30
- 35
- 40
- 45
- 50
- 55
- 60
- 65
- 70
- 75

the mercury to open the circuit through the electrodes when the coil is energized and close the circuit when the coil is deenergized, said means, quantity of mercury and electrodes being so proportioned as to cooperate with the time delay device to close the circuit through the electrodes after said coil remains energized for a predetermined period of time.

15. A front contact relay adapted to open and 10 close an electrical circuit whenever the relay is intermittently operated at or above a predetermined frequency, said relay comprising the combination of a container, a pair of electrodes in the container, a quantity of mercury in the container, 15 movable means for shifting the mercury with relation to the electrodes to close or open the electrical circuit through the electrodes, and a coil for operating said movable means to shift the mercury to close the circuit through the electrodes when the coil is energized and open the circuit when the coil is deenergized, said means, quantity of mercury and electrodes being so proportioned as to cooperate to close the circuit through the electrodes after said means remains 20 at rest for a predetermined period of time at any point in its movement.

16. A front contact relay adapted to open and 30 close an electrical circuit whenever the relay is intermittently operated at or above a predetermined frequency, said relay comprising the combination of a container, a pair of electrodes in the container, a quantity of mercury in the container,

movable means for shifting the mercury with relation to the electrodes to close or open the electrical circuit through the electrodes, and a coil for operating said movable means to shift the mercury to close the circuit through the electrodes when the coil is energized and open the circuit when the coil is deenergized, said means, quantity of mercury and electrodes being so proportioned as to cooperate to close the circuit through the electrodes after said coil remains 10 deenergized for a predetermined period of time.

17. A front contact relay adapted to open and 15 close an electrical circuit whenever the relay is intermittently operated at or above a predetermined frequency, said relay comprising the combination of a container, a pair of electrodes in the container, a quantity of mercury in the container, movable means for shifting the mercury with relation to the electrodes to close or open the electrical circuit through the electrodes, a 20 time delay device associated with the container, and a coil for operating said movable means to shift the mercury to close the circuit through the electrodes when the coil is energized and open the circuit when the coil is de-energized, said means, quantity of mercury and electrodes being so proportioned as to cooperate with the time delay device to close the circuit through the electrodes after said coil remains deenergized for a 25 predetermined period of time.

CARL H. LARSON. 30
